(57) **CLAIM**

I claim the ornamental design for a pet bowl, as shown and described.

DESCRIPTION

FIG. 1 is a top right corner perspective view of the pet bowl showing my new design;
FIG. 2 is a bottom left corner perspective view thereof;
FIG. 3 is a front elevation view thereof;
FIG. 4 is a right side view thereof, the left side view being identical;
FIG. 5 is a top plan view thereof; and,
FIG. 6 is a bottom view thereof.

1 Claim, 6 Drawing Sheets**FIG. 1**

FIG. 2

FIG. 3

FIG. 4

FIG. 5

FIG. 6
